Primary Examiner — David Muller

(57) **CLAIM**

The ornamental design for a relaxation apparatus for care environment, as shown.

DESCRIPTION

FIG. 1 is a perspective view showing my design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.
The broken line showing of parts of the drawings is included for the purpose of illustrating use and environment and forms no part of the claimed design.
